[57] **ABSTRACT**

A process for oxidizing polyalkyl monoaromatic hydrocarbons to the corresponding polycarboxylic monoaromatic acid by contacting them with an aqueous solution of ammonium dichromate at elevated temperatures. The product of the reaction is the ammonium salt of the corresponding polycarboxylic acid, which, upon acidification, yields the free organic polycarboxylic acid.

METHOD FOR OXIDIZING HYDROCARBONS

This application is a continuation-in-part of U.S. application Ser. No. 408,884, filed Nov. 4, 1964, now U.S. Pat. No. 3,560,559.

The present invention relates to the oxidation of cyclic hydrocarbons and partially oxidized cyclic hydrocarbons by ammonium chromate or dichromate. More particularly, the invention relates to the oxidation of these compounds by reaction with aqueous ammonium chromate or dichromate.

Prior oxidation processes utilizing a chromium (VI) oxidant are economically unfeasible for commercial application because they result in the formation of large amounts of alkali metal halides or sulphates which are of low value. According to the present process, the production of large amounts of low value by-products is avoided and the reduced chromium compound, Cr_2O_3 , is regenerated to the dichromate while producing the more economically attractive ammonium salts.

The following is a general description of the present process. An understanding of the major steps of the process and their inter-relation may be facilitated by reference to the accompanying flow diagram.

A feedstock containing cyclic hydrocarbons and/or partially oxidized cyclic hydrocarbons is contacted with an aqueous solution of ammonium dichromate at elevated temperatures to form various oxidation products. Depending upon the pH of the reaction media, the oxidation product formed will be either the ammonium salt of an organic carboxylic acid or an organic carboxylic acid amide.

The primary products formed by the present invention are carboxylic acids or carboxylic acid amides. At pH levels of about 7 or below, the predominant product is the ammonium salt of an organic carboxylic acid which can be acidified to form the free acid. When the pH of the reaction media is above about 7, high yields of carboxylic acid amides are formed.

During the oxidation reaction, the ammonium dichromate is reduced to Cr_2O_3 which precipitates from the reaction mixture and is removed by conventional means. After being removed from the reaction zone, the Cr_2O_3 is mixed with ammonium hydroxide and oxidized with oxygen to form ammonium chromate which can be converted to ammonium dichromate. The regeneration of Cr_2O_3 is enhanced by conducting it in the presence of catalysts, such as copper sulphate or cobalt naphthenate. In a preferred embodiment, the Cr_2O_3 is regenerated in the presence of a mixture of cupric sulphate and sodium sulphate. The copper ions, which detrimentally effect the oxidation reactions, are precipitated from the regeneration mixture by removing ammonia from the mixture after completion of the regeneration period.

Following the removal of the Cr_2O_3 from the oxidation product, water and ammonia are flashed from the hot reaction mixture. The oxidation product is then recovered. When the product is the ammonium salt of an organic carboxylic acid, it is reacted with a non-oxidizing strong acid to form the organic free acid and an ammonium salt of a strong acid.

The regeneration of Cr_2O_3 to form ammonium chromate is more fully disclosed in application Ser. No. 373,879, filed June 9, 1964, now U.S. Pat. No. 3,393,972, and Ser. No. 402,958, filed Oct. 9, 1964,

now U.S. Pat. No. 3,369,861, both assigned to the assignee of this application.

The present invention has utility in the oxidation of a wide variety of hydrocarbons and partially oxygenated hydrocarbons. Examples of suitable feedstock materials include the xylenes, mesitylene, durene, propylbenzene, cymene, toluic acid, toluol, tolualdehyde, 2,6-dimethylnaphthalene, acenaphthene, acenaphthylene, 1-methyl-4-isopropylnaphthalene, 1,4-dimethyl-4-isopropylnaphthalene, 1,3-dimethylanthracene, 2,7-dimethylanthracene, 1,7-dimethylphenanthrene, 1,6-diisopropylnaphthalene, 1,2,4-trimethylanthracene, 7-methyl-1-ethylphenanthrene, 1-methyl-4-isopropylanthracene, 1,3,6,8-tetramethylanthracene, 9,10-diethylphenanthrene, cyclohexane, cyclopentane, cycloheptane, cyclohexanol, and cyclopentanol. Generally, any aromatic compound substituted with a lower alkyl group can be used as a feedstock. Mixtures of hydrocarbons can also be oxidized by this procedure. An example of such a mixture is cycle oil, a product of the catalytic refining of petroleum (*Industrial and Engineering Chemistry*, Vol. 38, pp. 136-(1946) at page 137). Generally these products are a mixture of alkylnaphthalene, anthracene, etc.

The oxidation of the feedstock is generally accomplished by mixing the alkylaromatic or cycloaliphatic compound with an aqueous ammonium dichromate solution and heating. The reaction conditions may vary over fairly wide ranges. The oxidation temperatures which are utilized vary widely with the raw material. Thus, temperatures from about 200° to 325°C are suitable temperatures for the preparation of the carboxylic acid amides, preferably carried out in the range of from 160° to 325°C. The pH of the oxidation reaction mixture can vary from about 1 to about 11, with a pH below about 7 being preferable for the preparation of high yields of organic carboxylic acid products. The ratio of dichromate equivalents to oxidizable carbon atoms which are useful in the process range from about 0.5 to 1 to in excess of 3 to 1. A ratio in the range of from about 1.5:1 to 2.5:1 is preferred. High yields are obtained with relatively short reaction times on the order of about 15 minutes to 30 minutes. The reaction may be conducted at ambient pressures.

The oxidation reaction mixture is in two phases and the known techniques for increasing miscibility and surface area are generally applicable to the instant process. For example, surfactants can be added to the mixture to reduce the surface tension between the two phases and stirring or bubbling can be used to increase interfacial area.

After oxidation is substantially completed, ammonia and steam are removed from the reaction zone, preferably by flashing off these compounds. The precipitated chromic oxide is then removed, usually by filtration, or by other means, such as decantation. The ammonium salts of the organic acids in the reaction medium are then neutralized with a non-oxidizing strong acid, such as sulphuric acid, hydrochloric acid, hydrobromic acid, phosphoric acid, etc., to form the free organic acid which precipitates and is removed by filtration, decantation or similar well-known methods.

In a preferred cyclic process, the Cr_2O_3 is regenerated to form ammonium dichromate. The chromic oxide is transferred to a regenerator, usually a pressure resistant vessel or autoclave, in which it is reacted with oxygen and aqueous ammonia. Generally the chromic

oxide is preferably mixed with aqueous ammonia, most of which is derived from the ammonia removal step which may be conducted as part of the process. The aqueous ammonia solution may contain from about 4% to 80% by weight of ammonia, about 15% being preferred, and the mole ratio of ammonia to chromic oxide should be from about 2 to 160. Oxygen, in the form of pure oxygen, oxygen enriched air, air, and oxygen-nitrogen mixtures, is then added to the autoclave containing this mixture to provide an oxygen partial pressure of from about 20 to in excess of 500 psi and preferably about 200 psi. The reaction mixture is then heated for at least about 15 minutes at a temperature of from 140° to 225°C and preferably about 180°C. The reaction is conducted in the presence of copper sulphate and sodium sulphate. In this manner, about 90% of the spent Cr(III), in the form of Cr₂O₃, may be converted into Cr(VI) in the form of ammonium chromate.

After the regeneration of chromic oxide is completed, ammonia is removed from the reaction vessel. Preferably, ammonia and steam are flashed from the reaction vessel. Additional heating at from about 150° to 250°C can be used to flash off excess ammonia, thereby reducing the pH of the reaction mixture and precipitating copper ions as the insoluble hydroxide. Ammonium dichromate is formed from ammonium chromate as the ammonia is removed. The flashed ammonia is then recycled to the chromic oxide regeneration vessel.

Having described the invention in general and in terms of a preferred cyclical mode of operation, it is believed that the following detailed examples of preferred procedures will assist towards a better understanding of the process.

The invention will also be better understood by reference to the flow diagram of the process which is set forth in the single FIGURE of the accompanying drawing.

EXAMPLE 1

A mixture of 154 ml of distilled water, 50.7 g (0.201 mole) of reagent ammonium dichromate having an initial pH of 3.65 and 9.13 ml (0.074 mole) of p-xylene were placed in a 300 ml rocking autoclave and heated to 225°C. The mixture was allowed to react for a period of 60 minutes with continuous rocking of the autoclave.

The reaction products of the p-xylene oxidation were then filtered and acidified with hydrochloric acid to a pH of about 1 to precipitate the aromatic acids. A 97.8% conversion of the p-xylene was obtained and a total mixed acid yield of 86.5% was recovered. Upon analysis, it was found that about two-thirds of the mixed acids were terephthalic acid and most of the balance was terephthalamic acid. Base hydrolysis of the mixed acids produced over 99% pure terephthalic acid and ammonia gas.

The acidification of the oxidation products with hydrochloric acid also produced ammonium chloride. This salt was recovered by filtration, purified by recrystallization, and then stored. In large scale commercial process, the by-product ammonium chloride can be sold, thus rendering the process more attractive than prior methods in which sodium chloride is produced.

EXAMPLE 2

Following the procedure of Example 1, a mixture of

154 ml of water, 50.7 g (0.201 mole) of ammonium dichromate and 15.62 gms (0.10 mole) 2,6-dimethyl-naphthalene was added to a 300 ml rocking autoclave. The reaction was conducted during continuous rocking of the autoclave at 225°C for 1 hour. After flashing off excess ammonia, the oxidation reaction filtrate was acidified with hydrochloric acid to a pH of approximately 1 to precipitate naphthalene-2,6-dicarboxylic acid. The yield was 38.8%.

10 Following the procedure of Example 1, a number of oxidations were conducted using a variety of feedstock materials and varying some of the reaction conditions to determine the effect such changes may have on yield.

15 The oxidation of o-xylene with aqueous (NH₄)₂Cr₂O₇ was conducted following the procedure of Example 1. In each case, 0.201 mole of (NH₄)₂Cr₂O₇ and 0.123 mole of o-xylene was reacted in 154 ml of H₂O for 60 minutes, with an initial pH of about 3.5. The ammonium dichromate solution was free from residual cupric sulphate. The results of a series of such runs at varying temperatures appear in Table 1.

Table 1

Run No.	Reaction Temp. (°C)	o-Toluic Acid Percent Yield	o-Toluamide Percent Yield	Phthalic Acid Percent Yield
1-1	175	3.21	0.22	0.1
1-2	200	9.93	1.84	2.9
1-3	225	11.15	4.97	1.8
1-4	250	4.09	3.53	1.1
1-5	250	6.82	5.29	1.3
1-6	275	20.2	5.22	0.0
1-7	300	19.23	6.72	1.7

35 From the data of Table 1, it is evident that the major product of the oxidation of o-xylene with ammonium dichromate is o-toluic acid. Relatively minor amounts of o-toluamide and phthalic acid are also produced. 40 The yield of o-toluic acid tends to increase at more elevated temperatures with the highest yield being obtained at 275°C. The yield computed from the results of the experiments reported in Table 1 and Table 2 is based on the mole percent of aromatic acid or amide produced per mole of o-xylene charged.

45 Another series of runs was conducted under exactly the same conditions as were employed in the reactions reported in Table 1, but the aqueous ammonium dichromate solution contained 6.8 grams of residual cupric sulphate catalyst. The results of this series of reactions are reported in Table 2.

Table 2

Run No.	Reaction Temp. (°C)	o-Toluic Acid Percent Yield	o-Toluamide Percent Yield	Phthalic Acid Percent Yield
2-1	175	0.00	0.00	0.00
2-2	200	3.10	7.17	0.4
2-3	215	6.55	13.40	0.3
2-4	225	1.16	8.52	0.1
2-5	235	2.24	10.29	0.3
2-6	250	0.66	1.83	0.7
2-7	275	0.00	0.00	0.00

65 It is readily apparent from the data of Table 2 that the presence of a substantial amount of residual copper ions in the oxidant solution sharply reduces the yield of

Table 4

Run No.	p-Xylene ml	H ₂ O ml	Conc. NH ₄ OH ml	Reaction Temp. (°C)	p-Xylene Percent Conversion	Acids	Percent yield p-Toluamide
4-1	9.13	154	0	180	97.7	1.3	0
4-2	9.13	154	0	200	88.8	25.6	0
4-3	9.30	154	0	210	—	37.5	6.9
4-4	9.13	124	30	225	85.5	39.4	6.5

valuable aromatic acids, regardless of variation in temperature. This demonstrates the importance of the copper ion removal step before the recirculation of the regenerated oxidant solution.

A number of oxidation reactions were also conducted utilizing p-xylene as the alkyl aromatic compound. Still following the general procedure of Example 1, 0.201 mole of (NH₄)₂Cr₂O₇ was reacted with varying amounts of p-xylene in 154 ml of H₂O. The reactions were conducted at a temperature of 225°C for 60 minutes. The initial pH of each reaction mixture was adjusted to 3.65. The yields are computed as the mole percent of organic acid or amide produced per mole of hydrocarbon charged to the autoclave. Conversion is the mole percent of a given reaction component converted to other products and includes any unrecovered portion of the component. The results of these runs are reported in Table 3.

The data contained in Table 3 indicates that substantial yields of terephthalic acid may be obtained by the oxidation of p-xylene with ammonium dichromate. It also shows that higher yields are obtained at higher mole ratios of (NH₄)₂Cr₂O₇ to p-xylene. A commensurate decrease in the yield of secondary products is experienced as the (NH₄)₂Cr₂O₇ to p-xylene ratio is increased.

dium contained 6.8 g of cupric sulphate. The results of these reactions are set forth in Table 4. The percent yield of acids below includes terephthalic plus terephthalamic acids.

The data of Table 4 indicate that higher yields of mixed terephthalic and terephthalamic acids are obtained at more elevated temperatures, the maximum yield being obtained at a reaction temperature of 225°C. However, the results are relatively poor when compared with the yields obtained from the reactions reported in Table 3 where an ammonium dichromate oxidant solution substantially free from copper ions is employed. This again demonstrates the importance of the removal of copper ions from the oxidant solution.

A feedstock of 2,6-dimethylnaphthalene was also subjected to oxidation by aqueous ammonium dichromate in another series of reactions conducted according to the general procedure of Example 1. The reaction was conducted with 50.7 g (0.201 mole) (NH₄)₂Cr₂O₇ and varying amounts of 2,6-dimethylnaphthalene in 154 ml of water. The initial pH of each reaction media was 3.65. In addition to varying the amount of the alkyl aromatic reactant, the reaction times and temperatures were also varied from one run to another. The different conditions employed in each reaction and the results obtained appear in Table 5.

Table 3

Run No.	p-Xylene (ml)	Percent Conversion	(NH ₄) ₂ Cr ₂ O ₇ p-Xylene Mole Ratio	Terephthalic Acid	Percent Yield Terephthalic Acid	p-Toluamide
3-1	12.34	100	2.00	59.1	13.5	3.3
3-2	9.92	80.4	2.50	59.1	17.8	2.9
3-3	9.29	75.4	2.68	52.8	15.8	2.6
3-4	9.13	74	96.6	2.74	70.6	12.0
3-5	9.13	74	97.8	2.74	72.3	14.2
3-6	9.13	74	97.8	2.74	70.5	13.6
3-7	8.26	67	—	3.00	78.8	3.25

Table 5

Run No.	2,6-Dimethylnaphthalene grams	Percent Conversion	Reaction Temperature (°C)	Reaction Time Hours	Naphthalene-2,6-Dicarboxylic Acid Percent Yield
5-1	15.62	0.10	59.4	225	1
5-2	15.62	0.10	42.9	215	1
5-3	11.55	0.07	—	225	1
5-4	11.55	0.07	82.7	225	1
5-5	11.55	0.07	50.0	215	1
5-6	11.55	0.07	52.0	200	4
5-7	15.62	0.10	75.0	215	4

Another series of reactions was conducted to determine the effect of (1) reaction temperature variations and (2) the presence of copper ions, as cupric sulphate, on the oxidation of p-xylene with ammonium dichromate. The same general procedure was employed as in the preceding oxidations. The amount of reactants was the same in each run, 50.7 g (0.201 mole) of (NH₄)₂Cr₂O₇ and 9.13 ml of p-xylene. The reaction me-

65 As shown in Table 5, substantial amounts of naphthalene-2,6-dicarboxylic acid are produced according to this process. The yield of the acid tends to be higher at more elevated reaction temperatures as may be seen by comparing Run Nos. 5-1 and 5-2, 5-4 and 5-5, 5-3 and 5-5. A comparison of the results of Run Nos. 5-2 and 5-5 also indicates that a higher acid yield is obtained at higher mole ratios of (NH₄)₂Cr₂O₇ to

2,6-dimethylnaphthalene. Some improvement in yield at longer reaction times is also evident from a comparison of Run Nos. 5-2 and 5-7.

A further study of the effect of reaction time on the oxidation of 2,6-dimethylnaphthalene was made in a series of reactions in which only the time was varied. In these runs, 50.7 g (0.201 mole) of $(\text{NH}_4)_2\text{Cr}_2\text{O}_7$ and 15.62 g (0.10 mole) of 2,6-dimethylnaphthalene in 154 ml H_2O were reacted at 215°C. The results are set forth in Table 6.

Table 6

Run No.	Reaction Time Hours	2,6-Diacid Yield Mole %	2,6-Dimethylnaphthalene % Conversion	2,6-Diacid Selectivity
6-1	1	24.0	42.9	0.560
6-2	2	40.29	64.4	0.635
6-3	4	50.1	75.05	0.667
6-4	6	60.2	80.4	0.749
6-5	8	46.1	78.6	0.586

The data of Table 6 demonstrate that the yield of the dicarboxylic acid increases with increase in the reaction time up to about 6 hours. A corresponding increase in 2,6-dicarboxylic acid selectivity is also experienced as the time is increased progressively from 1 to 6 hours in Run Nos. 6-1 through 6-4. However, between 6 and 8 hours reaction time, a decrease in yield and selectivity is noted, due perhaps to some degradation or recombination of the products. In this context, selectivity refers to the fraction of converted 2,6-dimethylnaphthalene that is oxidized to naphthalene 2,6-dicarboxylic acid.

A feedstock of m-xylene was also oxidized with aqueous $(\text{NH}_4)_2\text{Cr}_2\text{O}_7$. In these reactions, 50.7 g (0.201 mole) $(\text{NH}_4)_2\text{Cr}_2\text{O}_7$ and 9.13 ml (0.074 mole) m-xylene in 154 ml H_2O were reacted for 60 minutes. The results appear in Table 7.

Table 7

Run No.	Reaction Temp. (°C)	m-Xylene Percent Conversion	m-Toluamide Percent Yield	Isophthalic Acid Percent Yield	Isophthalamic Acid Percent Yield
7-1	215	93.2	4.1	62.7	20.0
7-2	225	93.9	2.8	61.0	13.5
7-3	235	—	1.8	63.0	27.2

The data in Table 7 show that a substantial yield of isophthalic acid is obtained by the oxidation of m-xylene according to this process. A significant yield of isophthalamic acid is also produced. The variation in temperature from 215°C to 235°C does not produce a great increase in diacid yield, but a large yield of isophthalamic acid was secured at 235°C.

Mixed xylenes (50% m-, 25% o- and 25% p-xylene) were also subjected to ammonium dichromate oxidation and substantial amounts of mixed acids were produced.

A number of other feedstocks were oxidized according to the present process with good results. In each

case, 50.7 g (0.201 mole) $(\text{NH}_4)_2\text{Cr}_2\text{O}_7$ was reacted with the feedstock in 154 ml H_2O for 60 minutes. The results of these reactions are set forth in Table 8. In this data, weight percent yield is

weight of product/weight of starting material $\times 100$.

Table 8

Run No.	Org. Start. Material	Temper-ature (°C)	Products	Con-versation Percent
8-1	0.050 mole durene	225	6.56 wt. % yield mixed acids including pyromellitic acid	90.5
8-2	0.050 mole durene	225	11.78 wt. % yield mixed acids including pyromellitic acid	87.2
8-3	15.5 ml LCCO extract	215	12.5 wt. % yield mixed acids	—
8-4	0.1 mole cyclohexanol	215	18.0% adipic acid	—

As mentioned before, when the pH of the reaction media is in excess of about 7, substantially increased yields of carboxylic acid amides can be produced. This embodiment of our invention will be better understood by resorting to the following examples and tables.

EXAMPLE 3

300 ml rocking bomb was charged with 9.13 ml p-xylene, 50.7 g ammonium dichromate, 100 ml concentrated ammonium hydroxide (30% NH_3) and 54 ml distilled water. The pH of the aqueous phase before reaction was 10.42. The reaction mixture was then heated at 225°C for 60 minutes, after which the pH of the aqueous phase was 10.75. The aqueous effluent remaining after the completion of the oxidation reaction

50 was refluxed and then acidified to pH_1 with concentrated HCl . A 20.7% yield of terephthalamic acid was produced, based on charged p-xylene and determined by the neutralization equivalent of the product.

55 Following the general procedure of Example 3, a number of other oxidation reactions were conducted using p-xylene feedstock. The only departure from Example 3 was in the adjustment of the initial pH by the addition of ammonia or sulphuric acid from run to run. Otherwise, the same amounts of reactants and the same reaction condition was employed. The results appear in 60 Table 9. The results of Example 3 are also included in the Table for purposes of comparison.

Table 9

Run No.	Initial pH	Final pH	p-Toluamide Percent Yield	Terephthalamic Acid Percent Yield	Terephthalic Acid Percent Yield	p-Xylene Percent Conversion
9-1	1.42	8.95	1.3	11.1	73.2	95.1
9-2	2.00	8.95	0.2	11.1	73.6	93.9
9-3	2.90	9.20	1.5	11.8	76.8	95.5
9-4	3.65	9.05	1.9	12.0	70.6	96.6

Table 9

Run No.	Initial pH	Final pH	p-Toluamide Percent Yield	Terephthalamic Acid Percent Yield	Terephthalic Acid Percent Yield	p-Xylene Percent Conversion
9-5	7.08	10.08	3.8	17.0	68.8	96.1
9-6	9.45	10.13	5.2	18.9	61.6	97.4
Ex. 3	10.42	10.75	5.4	20.7	49.0	99.0

From the data in Table 9, it is evident that a sharply increased yield of terephthalamic acid and p-toluamide is obtained at pH levels above about 7. At lower pH levels, Run Nos. 9-1 through 9-4, aromatic acid production is favored.

In the present data, yield is the mole percent of product per mole of alkyl aromatic charged. Conversion is the percent of a given reaction component converted to other products including any unaccounted for portion of the reaction component

Reactions were also conducted according to the procedure of Example 3 using o-xylene as the feedstock. In each case, 9.32 ml of o-xylene was mixed with 50.7 g of ammonium dichromate in 154 ml of water. The initial pH of the reaction mixture was adjusted to the desired level by the addition of 10% H_2SO_4 or 58% NH_4OH to the reaction mixture. The reaction was carried out at 225°C for 60 minutes. The results of the runs appear in Table 10.

Table 10

Run No.	Initial pH	Final pH	o-Toluic Acid Percent	o-Toluamide Percent	Phthalic Acid Percent
10-1	2.01	9.25	15.2	6.4	4.0
10-2	7.48	9.95	15.2	15.4	4.3
10-4	10.20	9.90	14.2	15.2	4.2

The data of Table 10 clearly show that more than twice as much o-toluamide is produced by reaction at a pH above 7, than is formed at lower relatively acidic pH levels.

EXAMPLE 4

A 300 ml rocking bomb was charged with 8.90 ml of a feedstock of mixed xylenes, containing 50% m-xylene, 25% o-xylene and 25% p-xylene, and 50.7 g $(NH_4)_2Cr_2O_7$ in 154 ml of water. The pH of the mixture was adjusted to 2.0 by additions of H_2SO_4 and/or NH_4OH . The mixture was then reacted at 225°C for 60 minutes. A yield of 3.8% of mixed amides was obtained.

EXAMPLE 5

Example 4 was repeated, but the initial pH of the reaction mixture was adjusted to 6.9. A yield of 6.6% of mixed amides was obtained.

EXAMPLE 6

Example 4 was repeated, but the initial pH of the reaction mixture was adjusted to 9.8. A yield of 7.9% of mixed amides was obtained.

The results of Examples 4, 5 and 6 also demonstrate that conducting the oxidation of alkylaromatic compounds at a pH about 7 or higher results in a substantial increase in amide yield over that obtained by reacting at relatively acid pH levels.

It will be understood that various changes in the details of the process may be made by those skilled in the art without departing from the spirit of our invention. It is our invention, therefore, to be limited only as indi-

cated by the scope of the following claims.

What is claimed is:

1. A method for oxidizing a polyalkyl monoaromatic hydrocarbon feedstock to the corresponding polycarboxylic monoaromatic acid comprising:

a. reacting the feedstock with aqueous ammonium dichromate in an equivalent ratio of from about 0.5:1 to about 3:1 of said ammonium dichromate to oxidizable carbon atoms of said polyalkyl monoaromatic hydrocarbon and at a temperature of from 160°C to 325°C to produce chromic oxide and the ammonium salt of said polycarboxylic monoaromatic acid,

b. reacting the chromic oxide with oxygen in aqueous ammonia to produce aqueous ammonium chromate,

c. removing ammonia from said aqueous ammonium chromate to form aqueous ammonium dichromate, recycling the aqueous ammonium dichromate for the oxidation of additional feedstock, and

d. acidifying the ammonium salt of said polycarboxylic monoaromatic acid to precipitate the acid therefrom.

2. The method of claim 1 wherein said feedstock is a polymethyl substituted monoaromatic hydrocarbon.

3. The method of claim 2 wherein said feedstock comprises a member selected from the group consisting of mesitylene and durene.

4. The method of claim 3 wherein said feedstock comprises mesitylene and the corresponding polycarboxylic monoaromatic acid is trimesic acid.

5. The method of claim 3 wherein said feedstock comprises durene and the corresponding polycarboxylic monoaromatic acid is pyromellitic acid.

6. The method of claim 1 wherein said chromic oxide is separated from the ammonium salt of the said polycarboxylic monoaromatic acid prior to reaction with oxygen, and further wherein said ammonium salt of said polycarboxylic monoaromatic acid is precipitated by acidifying the ammonia free aqueous phase remaining after the reaction of the feedstock with the ammonium dichromate.

7. The method of claim 1 wherein said polyalkyl monoaromatic hydrocarbon feedstock comprises a member selected from the group consisting of mesitylene which is oxidized to trimesic acid and durene which is oxidized to pyromellitic acid wherein said feedstock is reacted with said aqueous ammonium dichromate to produce an aqueous phase in which is dissolved the ammonium salt of the product acid of the feedstock and to produce a chromic acid precipitate, and further wherein ammonia is removed from said aqueous ammonium chromate by heating said aqueous ammonium chromate to form aqueous ammonium dichromate and ammonia.

8. The method of claim 1 further comprising recovering ammonia generated during the process of recycling it as aqueous ammonia for reaction with said chromic oxide and oxygen to produce aqueous ammonium chromate.

9. The method of claim 1 wherein said chromic oxide, oxygen and aqueous ammonia are reacted in the presence of a cupric sulphate catalyst and sodium sulphate.

10. A method for oxidizing a polymethyl monoaromatic hydrocarbon feedstock to the corresponding polycarboxylic monoaromatic acid comprising:

- a. reacting the feedstock with aqueous ammonium dichromate in an equivalent ratio of from about 0.5:1 to about 3:1 of said ammonium dichromate to oxidizable carbon atoms of said polymethyl monoaromatic hydrocarbon and at a temperature of from 160°C to 325°C to produce a chromic oxide precipitate and an aqueous phase containing the ammonium salt of said monoaromatic acid,
- b. separating said chromic oxide and said aqueous phase,
- c. catalytically reacting the chromic oxide with oxygen in aqueous ammonia to produce aqueous ammonium chromate,
- d. removing ammonia from said aqueous ammonium chromate by heating said aqueous ammonium chromate to form aqueous ammonium dichromate,
- e. recycling the aqueous ammonium dichromate for the oxidation of additional feedstock, and
- f. acidifying the aqueous phase containing the ammonium salt of said monoaromatic acid to precipitate the acid therefrom.

11. The method of claim 10 wherein said feedstock comprises mesitylene and the corresponding polycarboxylic monoaromatic acid is trimesic acid.

12. The method of claim 10 wherein said feedstock comprises durene and the corresponding polycarboxylic monoaromatic acid is pyromellitic acid.

13. The method of claim 10 further comprising recovering ammonia generated during the process and recycling it as aqueous ammonia for reaction with said chromic oxide and oxygen to produce said aqueous ammonium chromate.

14. The method of claim 10 wherein said chromic oxide, oxygen and aqueous ammonia are reacted in the presence of a cupric sulphate catalyst and sodium sulphate.

15. The method for oxidizing a polymethyl monoaromatic hydrocarbon to produce the corresponding polycarboxylic monoaromatic acid comprising:

- mixing said hydrocarbon with aqueous ammonium dichromate, the equivalent ratio of said ammonium dichromate to oxidizable carbon atoms in said hydrocarbon being in the range of from 0.5 to 3,
- heating said hydrocarbon and aqueous ammonium dichromate in an oxidation reactor at a temperature of from 200°C to 325°C for at least 15 minutes to produce an aqueous phase containing the dissolved ammonium salt of said acid and to precipitate chromic oxide,
- separating said chromic oxide and said aqueous phase,
- mixing said chromic oxide with aqueous ammonia, the mole ratio of said ammonia to said chromic oxide being in the range of from 2 to 160,
- heating the mixture of chromic oxide and aqueous ammonia in an autoclave in the presence of a cupric sulphate catalyst and sodium sulphate to a temperature in the range of from 140° to 225°C, under an oxygen partial pressure of from 20 to 500 psi, to produce aqueous ammonium chromate containing some dissolved cupric sulphate,
- heating said aqueous ammonium chromate to form aqueous ammonium dichromate and ammonia and to precipitate hydrated cupric oxide,
- recycling said aqueous ammonium dichromate to said oxidation reactor for the oxidation of additional hydrocarbon, and
- acidifying said aqueous phase containing the dissolved ammonium salt of said acid to precipitate said acid.

16. The method of claim 15 wherein said hydrocarbon is mesitylene and said acid is trimesic acid.

17. The method of claim 15 wherein said hydrocarbon is durene and said acid is pyromellitic acid.

18. The method of claim 15 further comprising recovering ammonia generated during the process and recycling it to said autoclave.
